SAMUEL E. SPERRY, OF WOODHAVEN, NEW YORK, ASSIGNOR TO INTERNATIONAL TYPESETTING MACHINE COMPANY, OF NEW YORK, N. Y., A CORPORATION OF NEW YORK.
PUMP-ACTUATING MEANS FOR TYPE-CASTING MACHINES.

1,108,804.

Specification of Letters Patent. Patented Aug. 25, 1914.

Application filed January 29, 1913. Serial No. 745,042.

To all whom it may concern:

Be it known that I, SAMUEL E. SPERRY, a citizen of the United States, residing at Woodhaven, in the county of Queens and 5 State of New York, have invented new and useful Improvements in Pump-Actuating Means for Type-Casting Machines, of which the following is a specification.

The present invention relates to improvements in casting mechanism as employed in connection with type casting machines and is particularly applicable to casting mechanisms of the character used in machines of the well known linotype class.

10 Heretofore, it has been customary in machines of that class to actuate the plunger of the metal pump by a coiled compression spring placed above the pump lever, but experience has shown that springs of that type 15 are liable to buckle unless guiding means is provided to retain the spring in proper form. It has also been proposed to use tension springs to actuate the pump, but those springs were not positioned directly above 20 the pump lever where they would act with the greatest efficiency.

It is the object of the present invention to provide novel spring actuating means for the pump which embodies a helical tension 30 spring which will always retain its proper form and is placed directly above the pump lever where it will act with the greatest efficiency to effect the working strokes of the pump when permitted to do so by the pump- 35 controlling cam.

The present invention also provides simple and improved means for connecting the spring to the pump lever whereby the tension of the spring may be adjusted quickly 40 and easily and without displacing the spring, and this connection can be removed if necessary without disturbing the spring.

To this end, the invention consists in certain improvements, and combinations and 45 arrangements of parts, all as will be herein-after more fully described, the novel features being pointed out particularly in the claims at the end of the specification.

The accompanying drawing shows the 50 present invention applied to pump mechanism of the type usually employed in machines of the linotype class.

In this instance, 1 designates a portion of the cylinder of the metal pump which may 55 be of the type generally used in casting ma-

chines wherein the cylinder occupies a position within the metal pot and the lower end of the cylinder communicates with a spout or nozzle which serves to conduct the metal at each operation of the pump to the mold 60 in the well known manner.

2 designates the plunger which operates in the pump cylinder and serves to force metal therefrom and through the spout or nozzle when the plunger is forced downwardly. The plunger is attached to an upwardly extending rod 3 and the latter is pivotally connected to the pump-actuating lever 4, this lever being pivotally connected at 5 to the pump bracket 6 and the latter 70 may be secured, as usual, to the main frame of the machine. A roller 7 is mounted on the pump-actuating lever 4 and 8 shows a portion of the cam which controls the operation of the pump. The roller 7 on the pump 75 lever is forced against the cam 8 by spring pressure, and the cam is so shaped that it will permit the spring pressure acting on the pump lever to force the pump plunger downwardly to eject a supply of metal from 80 the pump and will lift the pump plunger to produce the return stroke thereof at appropriate intervals.

According to the present invention, a lug 9 is formed on or attached to the stationary 85 pump bracket 6, this lug having a bore 10 extending vertically through the center thereof, and the periphery of the lug is formed with a helical groove 11 in which are fitted the convolutions at the lower end 90 of a helical spring 12, the lower end of the spring being thereby secured or fixed to the lug. This helical spring is of the tension type, that is to say, it normally has a tendency to contract in the direction of its 95 axis, the upper end of the spring being secured to a head 13 which is also preferably provided with a helical groove 14 in which fit the convolutions at the upper end of the spring. The spring is located directly above 100 the pump-actuating lever 4 and it operates on the pump-actuating lever through the agency of a rod 15 which passes loosely through the bore 10 of the stationary lug 9 and its lower end rests in a pocket or 105 socket 16 formed in the upper side of the pump-actuating lever at a suitable point between the pivot 5 thereof and its point of attachment to the pump-actuating rod 3. The rod 15 in the present instance is con-

nected to the head 13 in a manner which enables the tension and strength of the spring to be adjusted as required, the upper portion of the rod, as shown, being threaded at 17 5 to engage the correspondingly threaded head 13, and a lock nut 18 may be provided for locking the rod 15 in different adjusted positions. To adjust the tension of the spring action on the pump, it is only necessary to 10 loosen the lock nut 18 and to turn the rod 15 in an appropriate direction. Also, the rod 15 may be removed by unscrewing it and withdrawing it upwardly through the head 13 without disturbing the spring. The 15 spring is always under tension and hence it will retain itself in proper form and position, and owing to its location directly above the pump-actuating lever, it will operate with the greatest efficiency to produce the 20 working strokes of the pump under the control of the cam.

I claim as my invention:—

1. In casting mechanism of the class described, the combination of a pump, a helical tension spring having one end thereof 25 fixed, and a rod adjustably connected to the free end of the spring, said rod extending through the spring and coöperating with the pump and being removable independently of 30 the spring.

2. In casting mechanism of the class described, the combination of a metal pump, a member for operating it, a helical tension spring having its lower end fixed directly 35 above said pump-operating member, and a rod connected to the upper end of the spring and extending downwardly through the spring and bearing on said operating member, said rod being removable while the 40 spring remains in position.

3. In casting mechanism of the class described, the combination of a metal pump, a helical tension spring having one end thereof fixed, a head coöperative with the opposite end of the spring, and a rod coöperative 45 with the pump to actuate it, said rod being

longitudinally adjustable through said head and extending through the spring.

4. In casting mechanism of the character described, the combination of a metal pump 50 having a lever for actuating it, a relatively fixed bracket having a lug thereon formed with a vertical bore above said lever, a helical tension spring having its lower end attached to said lug, and means connecting 55 the upper end of the spring to the pump lever, said connecting means extending axially through the spring and through the bore in said lug and being removable from the spring while the latter remains in position.

5. In a machine of the linotype class, the combination of the metal pump lever, the supporting frame or bracket, and an expanded helical spring mounted on the supporting frame above the pump lever having its lower end fastened to the frame and having means connecting its upper end to the pump lever, the connecting means passing through the spring whereby a downward 70 pressure is exerted upon the pump lever, and said connecting means being removable while the spring remains in position.

6. In a machine of the linotype class, the combination of the metal pump having a 75 lever for actuating it, a cam coöperative with said lever, a supporting frame, and a tension spring mounted above the pump lever and having means operatively connecting one end to the pump lever and having 80 its other end connected to the supporting frame, the tension of said spring maintaining the pump lever in coöperative relation with the cam and tending to actuate the pump.

In testimony whereof I have hereunto set my hand in presence of two subscribing witnesses.

SAMUEL E. SPERRY.
